A. B. CAMERON.
ORNAMENTAL PANEL.

No. 19,475.

Patented Dec. 10, 1889.

Fig. 1.

Fig. 2.

UNITED STATES PATENT OFFICE.

ALLAN B. CAMERON, OF WILLIAMSPORT, PENNSYLVANIA.

DESIGN FOR AN ORNAMENTAL PANEL.

SPECIFICATION forming part of **Design No. 19,475**, dated December 10, 1889.

Application filed November 12, 1889. Serial No. 330,076. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

Figure 1 represents my design, and Fig. 2 the same slightly modified.

My design consists of a series of regular diamond-shaped elevations A placed in line. Between said elevations A appear diamond-shaped elevations B and C. Upon the sur-

faces of the elevations B and C appear grooves 15 or channels D, which extend from the meeting-points of said diamonds B and C outward to the edges of said diamonds B and C. I may make the edges E of the diamonds A rounded, as shown in Fig. 1, or stepped, as 20 shown at E' in Fig. 2.

I claim—

The design for an ornamental panel, substantially as herein shown and described.

ALLAN B. CAMERON.
